UNITED STATES PATENT OFFICE.

CHARLES JELLINEK AND DAVID STERN, OF NEW YORK, N. Y.

CHAIR.

1,271,170.

Specification of Letters Patent.

Patented July 2, 1918.

Application filed August 8, 1916. Serial No. 113,779.

To all whom it may concern:

Be it known that CHARLES JELLINEK and DAVID STERN, citizens of the United States, residing in the city, county, and State of New York, have invented certain new and useful Improvements in Chairs, of which the following is a specification.

Our invention relates in general to a swinging chair for use in connection with 10 sewing machine stands, counters and like places where it is desired to move the chair from an inoperative position into an operative seating position and particularly relates to such a device designed to be mounted on a 15 sewing machine stand or other support normally subjected to vibratory movement.

One of the objects of the invention is to provide a simple form of seat of the class described which can be moved quickly and 20 easily into a seating position and which will automatically remove itself from its seating into an inoperative and out-of-the-way position when relieved of the weight on the seat.

A further object of the invention is to 25 provide such a swinging seat carried by a support with means for transmitting the weight from the seat directly to the ground or floor without necessarily transmitting the same through the support, but which means 30 will normally be in an inoperative position removed from the space beneath the seat.

Still another object of the invention is to provide a swing seat support which may be locked in position by the weight on the seat 35 and which position will be maintained as long as there is any material pressure on the seat and a still further object is to provide a seat which may be carried by a vibratory member but which will itself be free of any 40 vibration.

Various other objects and advantages of the invention will be in part obvious from an inspection of the accompanying drawings and in part will be more fully set forth in 45 the following particular description of one form of mechanism embodying our invention, and the invention also consists in certain new and novel features of construction and combination of parts hereinafter set 50 forth and claimed.

In the accompanying drawings:

Figure 1 is a side elevation of a preferred embodiment of our invention, shown folded into its inoperative position;

Fig. 2 is a view similar to the Fig. 1, but with the device shown in its operative seat-

ing position and shown swung at right angles to the position illustrated in Fig. 1;

Fig. 3 is a horizontal sectional view taken on the line 3—3 of Fig. 1 and showing in 60 dot and dash lines, the operative position of the device shown in side elevation in Fig. 2;

Fig. 4 is an enlarged vertical sectional view of the swinging bracket and support taken on the line 4—4 of Fig. 1; and 65

Fig. 5 is a transverse sectional view taken substantially on the line 5—5 of Fig. 2.

In the following description and in the claims, parts will be identified by specific names for convenience of expression but 70 they are intended to be as generic in their application to similar parts as the art will permit.

In the accompanying drawings, the chair is shown in the form of an attachment 75 designed to be supported from some suitable part 6 of a work-table or frame-work of a sewing machine or other suitable article of furniture. In this disclosure the member 6 may be considered as a part of a machine 80 structure subjected to vibration and jars. A support of any conventional form is fastened to the frame-work or part 6 as by means of bolts 8. The support includes three vertically spaced horizontal plates 9, 85 10, and 11, projecting from one side of the support and coactively constituting a bearing for a vertically disposed pivoting pin 12. A triangular shaped vertically disposed bracket 13 is rigidly connected to the pin 12 90 so as to swing horizontally about the pin as a pivot. The upper portion of the bracket is defined by a relatively long horizontally disposed arm 14, pinned to and extending laterally from the upper end of the pivoting 95 pin. The pivoted end of this arm rests upon the upper bearing plate 9, which is formed into a boss 15 to support the same. The bracket includes an inclined brace or reach member 16, one end of which is riveted to the arm 14 intermediate its ends. The lower end of the reach member is connected to the pin 12 adjacent its lower end and is designed to rest on the lower bearing plate 11. This lower bearing plate is provided with a plurality of sockets 17 in the form of apertures disposed in an arc concentrically positioned about the axis of rotation of the pivot pin.

The portion of the reach member 16 which rests on the lower bearing plate is provided 100 with a projection 18, in the form of a pin, 105 designed to engage in any one of the sockets 110

to prevent swinging movement of the bracket about the axis of the pivot pin when the bracket and its seat are in depressed position.

5 The bracket is normally held in raised position, so that the projection is disengaged from the socket. For this purpose a lifting spring 19 rests upon the intermediate plate 10 and bears against a collar 20 fixed to the 10 pivoting pin between the upper and intermediate plates. The bracket is normally swung into inoperative position as shown in full lines in Fig. 3 and for this purpose a swinging spring 21 is coiled about the upper 15 portion of the pivot pins, has one end affixed to the collar 20 and the opposite end affixed to the upper bearing plate 9 as shown more particularly in Fig. 4. The outer free end of the horizontal arm 14 is bent into a 20 depending arm 22 to which is pivoted the upper end of a prop 23. The opposite or lower end of the prop is provided with a ground engaging foot 24 designed to have an extensive bearing upon the ground or 25 floor to support the outer end of the bracket when in operative supporting position. The prop includes a vertical portion 25 extending upwardly from the foot 24 and has its upper end bent laterally to form an offset 30 portion 26 pivoted to the end of the depending arm 22.

A seat 27 includes a spindle 28 depending therefrom and slidably mounted for vertical movement in the outer part of the arm 14.

35 The lower portion of the spindle is reduced to form an extension 29 passed through a slot 30 in the offset portion 26 of the prop. The prop is thus pivotally and loosely connected to the spindle and is positioned between a shoulder 31 formed by the reducing of the spindle end and a pin 32 passed through the lower end of the extension 29. A lifting spring 33 is positioned between the arm 14 and the seat to constitute a cushioning device for the seat and to swing the prop into its inoperative raised position.

In operation, and considering the device in the inoperative position shown in Fig. 1, the user may swing the bracket horizontally 50 into any desired angular position and until the pin 18 is above one of the sockets 17. Pressure upon the seat, as by sitting thereon, is transmitted through the spring 33, places the same under tension, and acts through 55 the bracket to force the pin 18 into engagement with its correlated socket, thus locking the bracket against swinging movement. At the same time the depression of the spindle acts upon the prop to swing the same

60 from the inoperative inclined position shown in Fig. 1, into the vertical-ground-engaging position shown in Fig. 2. A further pressure on the seat will lower the same from the position shown in Fig. 2 until the shoulder 31 rests on and is supported by the off-

set portion 26 of the prop. When in its final operative position, any weight on the seat is transmitted directly and almost vertically to the ground. As the seat is not directly supported by the bracket any vibratory movement in the main supporting member 6 which might be transmitted to the bracket will have little, if any, effect upon the person sitting upon the seat, and in this way a non-vibratory seat is provided. The 70 depression of the bracket places the lifting spring 19 under compression and the rotation of the bracket forward into a seating position coils the spring 21. The effect of these springs, when pressure is relieved from the seat, is to cause the seat to be unlocked and moved out of the way. The tendency of the spring 33 is to raise the prop into the inoperative position shown; the spring 19 will act directly upon the bracket to disengage the projection from its engaging socket, thus permitting the coiled spring 21 to act on the bracket and swing the same into its inoperative position under the table or other out-of-the-way position. By the action of these springs it is seen that the device is entirely automatic in its movement into its inoperative position. The tension of the spring 19 may be so proportioned that any slight rising movement of the operator from the seat will have no effect upon the set position of the bracket but the entire removal of any weight from the seat will cause the same to move automatically and quickly into its out-of-the-way position.

100 It is frequently true that with devices of this character, the space directly below the position normally occupied by the seat is necessary for the positioning of other parts of the machine to which the device is attached or other articles. Accordingly the prop may be so designed that when moved into the inoperative position, it will clear any such obstacles and it is to illustrate this feature of the invention that the prop was shown to be bent into position to swing the foot 24 relatively close to the support 6 when in operative position.

105 While we have shown and described, and have pointed out in the annexed claims, certain novel features of our invention, it will be understood that various omissions, substitutions and changes in the form and details of the device illustrated and in its operation may be made by those skilled in the art without departing from the spirit of the invention.

110 Having thus described our invention, we claim:

1. In a device of the class described, a 115 bracket mounted for swinging movement about a vertical axis, means confining said bracket substantially to a horizontal plane, a supporting prop pivoted to the bracket, and designed to support the same from the 120

- ground and a seat supported in horizontal position by the bracket and operatively connected to the prop to move the same into supporting position automatically when weight is placed on the horizontally disposed seat.
2. In a device of the class described, a bracket mounted for swinging movement horizontally about a vertical axis, a supporting prop pivoted to the bracket and designed to support the same from the ground in all positions of the bracket, a seat carried by the bracket and operatively connected to the prop to move the same into supporting position automatically when weight is placed on the seat and resilient means for moving the prop into inoperative position toward the bracket when the seat is free of prop actuating weight.
3. In a device of the class described, a bracket mounted for swinging movement about a vertical axis, a supporting prop pivoted to the bracket and designed to support the same from the ground, a seat carried by the bracket and operatively connected to the prop to move the same into supporting position automatically when weight is placed on the seat and means for locking the bracket in position in its swing arc about said axis.
4. In a device of the class described, a bracket mounted for swinging movement about a vertical axis, a supporting prop pivoted to the bracket and designed to support the same from the ground, a seat carried by the bracket and operatively connected to the prop to move the same into supporting position automatically when weight is placed on the seat, means for locking the bracket in position and means for moving the bracket into unlocked position when relieved from the prop actuating weight.
5. In a device of the class described, a supporting member, a prop pivoted to the member and designed to reach to the ground, a seat provided with a spindle mounted for substantially vertical movement in said supporting member and connected to said prop to swing the same into engagement with the ground when the seat is depressed, means for holding the prop normally in an inoperative position, and means acting on the bracket for moving the same into an inoperative position.
6. In a device of the class described, the combination of a seat, a horizontally movable bracket for carrying the same, a support for transmitting weight on the seat directly to the ground and means normally acting on said support for moving the same from beneath the seat.
7. In a device of the class described, the combination of a seat, means for supporting the same in normal seating position, an additional support for transmitting weight on the seat directly to the ground, and means for normally acting on said support for moving the same from beneath the seat when the weight is removed from the seat.
8. In a device of the class described, the combination of a support, a bracket projecting horizontally from the support, a horizontally disposed seat carried by the bracket, a prop for transmitting the weight on the seat to the ground and means acting on the prop for raising the same into inoperative position toward the bracket when relieved of the weight on the seat.
9. In a device of the class described, the combination of a support, a bracket projecting horizontally from the support, a seat carried by the bracket, a prop for transmitting the weight on the seat to the ground, means acting on the prop for moving the same into inoperative position toward the support when relieved of the weight on the seat and means acting on the bracket to move the same together with the prop away from their operative position.
10. In a device of the class described, the combination with a support including a pivoting pin mounted therein and provided with a plate having a socket therein, a seat supporting bracket mounted to swing about said pin above said plate, a spring acting on said bracket for swinging the same about the pin, said bracket provided with a projection designed to seat in said socket to prevent rotary movement of the bracket when downward pressure is exerted on said bracket, and a spring normally acting on said pin to hold the projection clear of the socket whereby the bracket may be swung freely when free of weight thereon.
11. In a device of the class described, the combination with a support including a pivoting pin mounted therein and provided with a plate having a socket therein, a seat supporting bracket mounted to swing about said pin above said plate, said bracket provided with a projection designed to seat in said socket to prevent rotary movement of the bracket when downward pressure is exerted on said bracket, and resilient means acting on said bracket and tending normally to remove the projection from the socket and thus permit free rotary movement of the bracket.
12. In a device of the class described, a supporting member, a prop pivoted to the member and designed to reach to the ground, a seat provided with a spindle mounted for substantially vertical movement in said supporting member and connected to said prop to swing the same into engagement with the ground when the seat is depressed.
13. In a device of the class described, a supporting member, a prop pivoted to the member and designed to reach to the ground, a seat provided with a spindle mounted for substantially vertical movement in said sup-

porting member and connected to said prop to swing the same into engagement with the ground when the seat is depressed and means for holding the prop normally in an inoperative position.

14. In a device of the class described, a supporting member, a prop pivoted to the supporting member, said prop when in supporting position having a substantially vertical portion extending upwardly from the ground and an upper portion extending at an angle to the vertical portion, a seat provided with a spindle mounted for vertical movement in said support and connected to the angularly disposed portion of the prop to move the same.

15. In a device of the class described, a support, which may be subjected to vibratory movement, a bracket carried by said support, means engaging the bracket for holding the same in set position relative to the support, a seat carried by said bracket and means independent of the support for transmitting pressure on the seat directly to the ground whereby the person on the seat will not be subjected to the vibratory motion of the support.

Signed at New York, in the county of New York, and State of New York, this 26th day of July, A. D. 1916.

CHARLES JELLINEK.
DAVID STERN.
